UNITED STATES PATENT OFFICE.

CHARLES FORSMAN, OF NEW YORK, N. Y.

REGISTRY-BLOCK FOR ELECTROTYPESES.

SPECIFICATION forming part of Letters Patent No. 572,884, dated December 8, 1896.

Application filed February 6, 1896. Serial No. 578,232. (No model.)

To all whom it may concern.

Be it known that I, CHARLES FORSMAN, a citizen of the United States, residing in the city, county, and State of New York, have invented certain new and useful Improvements 5 in Registry-Blocks for ElectrotypeSES, of which the following is a specification.

This invention relates to a registry-block for electro typeS or plates, the object of the 10 invention being for the purpose of shifting the electro typeS or plates without unlocking them from the block in such a manner that in color or other printing a perfect registry of the electrotype with the ground is always obtained.

15 The invention consists of a frame in which is mounted an adjustable backing-plate, means for adjusting the backing-plate in the frame, an abutment-flange along one end and one side of the backing-plate, against which 20 the electro type or plate is abutted, and gripper-jaws which engage the free edges of the electroplate and force the same against the abutment-flange, so that the electroplate is firmly locked on the registry-block in such 25 position that it can be adjusted even to hair-breadths, all as hereinafter described, and then particularly claimed.

30 In the accompanying drawings, Figure 1 is a plan view of my registry-block for electro- plates. Fig. 2 is a longitudinal section of the same on line 2 2, Fig. 1. Fig. 3 is a broken detail plan view of one of the adjusting-shoes which are mounted in the frame of the block for adjusting the backing-plate. Fig. 4 is a 35 section on the line 4 4, Fig. 3, showing the backing-plate also; and Fig. 5 is a broken detail view of the main portion of the adjusting mechanism of the gripper-jaws which engage the electroplate.

40 Similar letters of reference indicate corresponding parts.

Referring to the drawings, A indicates a 45 rectangular frame which is provided at its upper inner corner with a rabbet-groove a, which in practice is of such size that a space of one-eighth of an inch is left all around the 50 backing-plate B, which rests in the rabbet-groove. The backing-plate B is of thin metal and is provided on its under side with a suitable 55 number of transverse and longitudinally-extending shoulders b, against which abut the shoes C, which are mounted in the main frame

of the registry-block. The shoes C are of suitable shape and number, there being shown six in the drawings, one at each end and two 55 at each side, said shoes being pivoted to the inner ends of screw-threaded shanks C', which engage in screw-threaded openings extending laterally through the frame A and have mounted thereupon in recesses d in the frame 60 A adjusting-nuts D, said nuts being capable of rotating on and engaging with the shanks of the shoes without moving longitudinally on the shanks.

The backing-plate B is provided along one 65 end and one side with an upwardly-projecting abutment-flange B' and at the opposite end and opposite side with slots b', which extend at right angles to the edges of the backing-plate. Projecting upwardly through 70 these guide-slots b' are a series of gripper-jaws E E', which may be separately adjusted, but which preferably, as shown in the drawings, are made adjustable in series, that is to say, three (E) of the same, which are arranged at 75 one side of the backing-plate, are adjusted together and separately from the other two gripper-jaws E', which are arranged at one end of the backing-plate, and which are also adjusted together. The gripper-jaws E, which 80 are guided in the slots at one side of the backing-plate, are adjusted by means of a rectangular frame F, the central bar F' of which is provided with a laterally-extending rod f, which is provided with a screw-thread, and 85 carries at its outer end the central one of the gripper-jaws E. This screw-threaded rod f passes through a screw-threaded opening in one of the ribs which go to make up the skeleton interior A' of the main frame, said rib being 90 provided with a lateral lug g, within a recess g' of which, that extends at right angles to the screw-threaded opening through which the rod f passes, is arranged an adjusting-nut G. At the end of the backing-plate B, in which 95 the gripper-jaws E' are guided, is also arranged an adjusting-frame H, which is similar in function to the adjusting-frame F and which moves at right angles to the latter. This adjusting-frame H, that carries the end 100 gripper-jaws E', is adjusted in a similar manner to the adjusting-frame F, that is to say, by a central screw-threaded rod h, projecting from the main bar of said frame and passing

through one of the ribs of the skeleton interior of the main frame, said screw-threaded rod h being adjusted by means of a nut h' , similar to the nut G .

5 My improved registry-block is adjusted and used as follows: The electroplate I , which is without the usual wooden-block mount, is first abutted with one end and one side against the end and side abutment-flange B' on the 10 backing-plate B . The nuts G h' of the adjusting-frames are then rotated in any suitable manner, so that the latter are moved, and consequently the gripper-jaws E E' caused to engage the other side and end of the electro- 15 plate, whereby the latter is firmly locked in position upon the backing-plate. The backing-plate, together with the electroplate mounted thereon, is now adjusted, according to the registration which is desired upon the 20 ground to be printed in colors, by means of the adjustable shoes C , which are adjusted by the rotation of the nuts D , said shoes C pivoting on the shanks C' , according to the angle at which the backing-plate and the elec- 25 troplate are arranged to the main frame A .

Of course the backing-plate and the electroplate may sometimes be adjusted with their sides and ends at right angles to the sides and ends of the main frame, in which case 30 the shoes C are arranged at right angles to the shanks C' . The slight play of one-eighth of an inch on either side of the backing-plate B is sufficient for practical purposes.

Of course, if desired, the main frame A 35 may be provided with suitable graduations, and the backing-plate be provided with an indicating-mark which is adapted to register with the graduations, so that the adjustment of the backing-plate upon the frame may be 40 accurately determined.

By means of my improved registry-block for electroplates it is possible to secure the accurate registry of the electroplate with the work without unlocking the same from the 45 chase. Other advantages of the invention are that the device will not shrink like the ordinary wood mounting on which the elec-

troplates are usually mounted; that the block is so solid it will not spring; the device will soon pay for itself, as the electroplates need 50 no wooden blocks, and underlaying directly under the plate is permitted without any chance of the sinking of the electroplate, as when mounted on wood blocks.

Having thus described my invention, I 55 claim as new and desire to secure by Letters Patent—

1. The combination of a main frame provided with a rabbet-groove, a backing-plate mounted on the main frame, in the rabbet- 60 groove, and having a space all around the edges of the same, means for adjusting the backing-plate in the rabbet-groove of the main frame, and means for locking an electroplate on the backing-plate, substantially as set forth. 65

2. The combination of a flat rectangular main frame, a backing-plate mounted on the main frame and provided with an abutment-flange at one end and one side, said backing-plate being of less length and width than the 70 space of the frame in which it is contained, gripper-jaws guided in the backing-plate and adapted in connection with the abutment-flange to lock an electroplate in position on the backing-plate, and means for adjusting 75 the backing-plate on the main frame, substantially as set forth.

3. The combination of a main frame, a backing-plate mounted on the main frame and provided with depending shoulders, longitudinally-adjustable shanks guided in the main frame, shoes hinge-jointed to said shanks and adapted to engage said shoulders, and means for locking the electroplate in position upon the backing-plate, substantially 80 as set forth.

In testimony that I claim the foregoing as my invention I have signed my name in presence of two subscribing witnesses.

CHARLES FORSMAN.
